UNITED STATES PATENT OFFICE

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

MANGLE.

1,175,509.

Specification of Letters Patent. Patented Mar. 14, 1916.

Application filed March 14, 1912. Serial No. 683,823.

To all whom it may concern:

Be it known that I, DANIEL M. COOPER, of Rochester, in the county of Monroe and State of New York, have invented certain new and useful Improvements in Mangles; and I do hereby declare the following to be a full, clear, and exact description of the same, reference being had to the accompanying drawings, forming a part of this specification, and to the reference-numerals marked thereon.

My present invention relates to improvements in mangles or ironing machines, particularly of the type adapted for ironing what is known as flat work, such as towels, handkerchiefs, sheets and the like, and embodying a series of rolls rotating against suitably shaped steam chests for ironing the goods on one side and an apron moving in engagement with a rotating drum for ironing the goods on the opposite side, and it has for a principal object to provide an improved mechanism for actuating the roll supports, to move the rolls bodily away from their coöperating surfaces.

Another object of my invention resides in the provision of means for indicating to the operator the distance through which the rolls move, when being lowered, so as to maintain a perfect control over the pressure exerted on the work.

Still another object of my improvement is the provision of certain novel features of construction whereby access may readily be had to the machine at the point where the work is carried from the drum to the top of the apron, and the operating parts may be easily moved out of their operative positions.

To these and other ends the invention consists in certain improvements and combinations of parts all as will be hereinafter more fully described, the novel features being pointed out in the claims at the end of the specification.

In the drawings: Figure 1 is a side elevation showing the application of a preferred embodiment of my improvements to a mangle of usual type; Fig. 2 is a longitudinal

vertical sectional view of the same; Fig. 3 is a sectional view on the line 3—3 of Fig. 2; Fig. 4 is a sectional view on the line 4—4 of Fig. 3; Fig. 5 is a plan view, partially in section, as indicated by the line 5—5 of Fig. 2; Fig. 6 is a detail sectional view on the line 6—6 of Fig. 5; Fig. 7 is a sectional view on the line 7—7 of Fig. 3; Fig. 8 is a sectional view on the line 8—8 of Fig. 3; Fig. 9 is a partial end elevation of the machine; Fig. 10 is a plan view showing the doffer-boards, and their support, the drum and rolls being omitted; Fig. 11 is a detail view in edge elevation of one of the doffer-boards; Fig. 12 is a view of a portion of the coöperating rolls which carry the work from the drum to the top of the apron; Fig. 13 is a sectional view on the line 13—13 of Fig. 10, and Fig. 14 is a similar view, showing the rolls separated, and the parts in inoperative position. Fig. 15 is a sectional view on the line 15^a—15^a of Fig. 9.

Similar reference numerals throughout the several figures indicate the same parts.

In the present embodiment, the invention is shown in connection with a known type of mangle or ironing machine, which embodies a main section 1 and a supplemental section 2 secured to the main section in any approved manner, it being understood that there may be two or more of such supplemental sections arranged together, and my invention is applicable to a single section or to a plurality of sections by merely modifying the present arrangement to accommodate the particular needs of the machine. The section 1 includes the drum 3, ironing rolls 4, 5 and 6, and the apron guiding roll 7, arranged adjacent to the drum, as shown in Fig. 2. The section 2 comprises steam chests 9 which are provided with concaved upper surfaces arranged to receive the rolls 10, the latter being mounted on movable supports, which in the present instance, comprise yokes 11 carried by the pivotally mounted arms 12 and adapted to be moved vertically in a manner that will hereinafter be set forth.

The parts of the machine are operated

from the main shaft or driving member 13 to which power is applied in any desirable manner. The driving member 13 communicates movement to the different rolls 5 through a driven member or sleeve 14 which carries a pinion 15 in engagement with the gear wheel 16. The driving member is adapted to be connected and disconnected to the driven member by means of a suitable clutch, comprising clutch elements 17 and 18 respectively, the latter being slidable on the driving shaft and operable by means of a shifter 19 which is pivoted at 20 and adapted to be actuated in a manner that I 15 will now describe. Fixed on the shaft 13 is a pinion 21 which is constantly in engagement with the gear wheel 22, the latter being loosely mounted on the shaft 23 which is normally stationary, and adapted to rotate in a manner that will appear presently. The shifter 19 is arranged to be actuated automatically, to stop movement of the rolls in case the operator's hand gets caught, or moves too far toward the feeding point of 25 the machine, and is actuated by means of the cam disk 24 fixed on the outer end of the shaft 23, the latter being provided with a plate 26, said plate carrying the spring-controlled pivotally mounted locking abutment 27 which is arranged to engage one of the projections 28 on the gear wheel 22, whereby the plate 26 and the cam disk 24 are rotated with the gear wheel, and the shifter is operated. The locking abutment 30 35 27 is provided with a tail piece 29, movable between the pins 30 and actuated by the spring 31. The locking abutment is held in normal or unlocking position by means of the lever 32 which is connected to the finger board 33 through the connecting rod 34, as usual in automatically controlled stop mechanisms of this type.

It is the purpose of my invention to provide for raising and lowering the rolls of the machine, by power actuated means, and from the driving shaft 13, either simultaneously with the movement of the other parts of the machine, or independently thereof, that is to say, when the machine is not in 45 operation, and to this end, I arrange the shaft 35 so as to be actuated from the gear wheel 22 in a manner that will presently be described, said shaft 35 serving to control the movement of the roll supports. Arranged on the shaft 35 are eccentrics 36 which are operatively connected to the rock arms 37, of angle levers which are in turn connected to the rolls 10 by means of the connecting rods 38, and to the rolls 5 and 6 by means of levers 39 and connecting rods 40. The rolls 5 and 6 are mounted on supports 41, pivoted at 42, as shown in Fig. 2. It will be seen that when the shaft 35 is rotated, the several roll supports are simul-

taneously actuated to move the rolls toward 65 and away from their respective engaging surfaces.

Movement of the shaft 35 is obtained from the driving shaft 13 in the following manner: The gear wheel 22 is provided on the opposite face from that already described with projections 43 which are adapted to engage and rotate the plate 44, the latter being keyed to the shaft 23 and having connected thereto a pinion 45 in engagement with a gear 46 which rotates in suitable bearings and carries a pinion 47 arranged to engage the gear wheel 48, the latter being keyed to the shaft 35. The plate 44 carries a locking abutment 49 which is pivotally mounted and provided with a tail piece 50 movable between pins 51 and controlled by a spring 52. The locking abutment 49 engages one or the other of the projections 43 on the gear wheel 22 85 when the tail piece 50 is released, the latter being held in normal position, as shown in Fig. 7, by means of a lever 53 which is arranged to be actuated by the treadle 54 through the crank arm 55 and connecting rod 56. The extent of movement of the shaft 35, and consequent movement of the roll supports, is controlled by a notched disk 57 which is keyed on the shaft 35 and engages the arm 58 carried by the lever 53 95 so that upon actuating the treadle 54, the shaft 35 will be rotated through the mechanism already described until the arm 58 drops into the next notch on the periphery of the disk 57. By providing three adjacent notches, as in the present embodiment, I am able to obtain a maximum, minimum, and intermediate degree of pressure of the rolls, as desired. When the roll supports are being lowered, the weight may be sufficient to cause a faster movement than that imparted by the power actuated means, and to prevent over-running the mechanism in this manner, I provide a suitable brake, which, in the present embodiment, includes 100 a cam 59 fixed on the shaft 35 and arranged to engage the lever 60. The lever 60 constitutes a part of a band-brake 61, acting upon the pulley 62, which is fixed upon the shaft 23, and cooperates with said 115 shaft so as to prevent the same from being moved by the weight of the rolls at a greater speed than that imparted by the driving mechanism. It is also desirable to provide means for enabling the operator of 120 the machine to determine accurately the position of the roll supports and the amount of pressure exerted when they are lowered, and to this end, in the present embodiment, I provide a stationary indicating plate 63 125 having suitable graduations marked thereon. Cooperating with said indicating plate is a hand or indicator 64 which is pivotally

mounted at 65, and operated from the yoke 11 by means of the connecting rod 66, which coöperates with an opening in the plate 67 carried by the yoke 11. The connecting rod 66 is held against upward movement relatively to the plate 67, while the spring 68 permits a yielding downward movement and overcomes any lost motion between the parts.

10 The particular form and arrangement of the indicating mechanism that I have just described is not essential to the object of my invention, and is merely one embodiment, illustrating the manner in which the 15 result may be obtained.

The apron 8 is guided around suitable rolls, as shown in Fig. 2, and as usual in this type of machine. The upper part of the apron travels around the roll 7, already 20 mentioned, and coöperating with said roll 7 are smaller rolls 69 and 70 which serve to guide the belts 71 that direct the work around the roll 7 to the upper surface of the apron 8 from which it is taken off by the 25 operators. It is sometimes desirable to obtain access to the exterior of the drum at the point where the roll 7 engages, and to this end, I mount said roll 7 and also roll 69 on movable supports, with means for holding 30 them normally in operative position. In the present embodiment, the roll 7 is mounted on the support 72 pivoted at 73 whereby the roll may be swung back to the position shown in Fig. 14, while the roll 69 is mounted on the support 74 pivoted at 75. In order to hold the rolls in operative position, I provide means for locking the supports together, such means preferably consisting of 35 a latch 76 pivoted to the support 72 and arranged to coöperate with a projection 77 on the support 74, and to hold the parts normally in coöperative engagement, as shown in Fig. 13. The roll 70 is held in inoperative position, as shown in Fig. 14, by means 40 of a locking member 78 which carries the projection 79 for engagement with the recess 80. The roll 70 is mounted in bearings fixedly supported on the rock shaft 81, which may be actuated by means of the hand 45 lever 82, similar levers 83 and 84 being arranged to control the position of the rolls 69 and 7. Also supported on the shaft 81 are the doffer-bars 85, which are preferably arranged as shown in Fig. 11. It is necessary 50 that the doffer-bars engage loosely against the drum by their own weight, and it is also desirable that they be thrown away from the drum upon the actuation of rock-shaft 81. To this end, the shaft 81 has secured thereto 55 the collars 86 with transverse cut away portions 87. Each doffer bar is mounted on a supporting member 88 journaled on the shaft 81 and provided with extensions 89 which engage said cut away portions 87,

and permit a slight lost motion between the 65 parts.

I claim as my invention:

1. In a mangle, the combination with a driving member, of a plurality of rolls, movable supports for the rolls, clutch controlled 70 means for rotating said rolls from the driving member, and separate clutch controlled means for actuating said movable supports from the driving member.

2. In a mangle, the combination with a 75 driving member, of a plurality of rolls, operative connections between the driving member and the rolls for rotating the latter, movable supports for the rolls, operative connections between the driving member and 80 the movable supports for moving the rolls bodily, and clutch controlled devices for operatively connecting and disconnecting the driving member with the rolls and with the roll supports so as to actuate the same either 85 simultaneously or independently.

3. In a mangle, the combination with a driving member, of a plurality of rolls, movable supports for the rolls, operative connections between the driving member and the 90 rolls and independent operative connections between the driving member and the roll supports, and means for rendering either of said connections inactive without affecting the movement of the other. 95

4. In a mangle, the combination with a driving member, of a driven member, a clutch element arranged on one of the members and coöperating with the other, a shifter connected to said clutch element, a 100 normally stationary shaft, a gear wheel loosely mounted on the last mentioned shaft and constantly in rotative engagement with said driving member, a plurality of rolls, movable supports for the rolls, a rotatable 105 shaft having operative connection with said movable supports, clutches arranged on opposite sides of the first mentioned gear wheel and adapted to coöperate therewith, means actuated by one of said clutches for operating the aforementioned shifter, and means actuated by the other clutch for operating said rotatable shaft. 110

5. In a mangle, the combination with a driving member, of a driven member, a 115 clutch element arranged on one of the members and coöperating with the other, a shifter connected to said clutch element, a normally stationary shaft, a gear wheel loosely mounted on the last mentioned shaft 120 and constantly in rotative engagement with said driving member, a plurality of rolls, movable supports for the rolls, a rotatable shaft having operative connection with said movable supports, clutches arranged on opposite sides of the first mentioned gear wheel and adapted to coöperate therewith, means actuated by one of said clutches for operat- 125

ing the aforementioned shifter, means actuated by the other clutch for operating said rotatable shaft, a cam mounted on the rotatable shaft, and a brake adapted to be actuated by said cam and coöperating with said normally stationary shaft.

6. In a mangle, the combination with a drum, of a roll arranged adjacent to the drum, a pivoted support for the roll, a sec-

ond roll arranged adjacent to the first mentioned roll, a pivoted support for the second roll, an abutment on one of the supports, and a pivoted latch on the other support arranged to engage said abutment.

DANIEL M. COOPER.
